UNITED STATES PATENT OFFICE.

ROBERT CHARLES TURNER, OF BIRMINGHAM, ENGLAND.

ENDLESS BAND GRINDING AND POLISHING MACHINE.

Application filed October 28, 1924, Serial No. 746,386, and in Great Britain March 13, 1924.

The invention relates to a grinding and polishing machine of the type using an endless band travelling over end pulleys and over the surface of a work table disposed intermediate of the pulleys.

In a machine of this type traversing screw mechanism has been provided to adjust the position of one of the end pulleys to stretch or tension the endless band, and clamping devices to rigidly fix the adjusted position. It has also been proposed to make the work table adjustable laterally in respect of the running to the endless band and to provide said table for total detachment from the frame of the machine.

The present invention further provides an endless band supporting and adjusting device comprising a substantially T-shaped frame and a bracket adjustably mounted on the frame.

The invention further provides for the ready detachment of the bracket, traversing screw mechanism and clamping devices as a unit.

The various novel features of the invention are described in the following specification with reference to the accompanying drawings and will be particularly pointed out in the claims.

The improved machine according to the invention is represented by the accompanying sheets of drawings.

Fig. 1 is a plan of the machine.

Fig. 2 is a front elevation of Fig. 1 with the endless band removed.

Fig. 3 is a sectional plan of a portion of Fig. 1 showing how the bracket carrying the adjustable band pulley is adjustably fitted to the slide-member of the machine's frame and is locked after adjustment.

Fig. 4 is a right-hand side elevation of Figs. 1 and 2.

Fig. 5 is a left-hand side elevation of Figs. 1 and 2.

Fig. 6 is a transverse sectional view taken substantially centrally of the bracket and clamping devices shown in Fig. 3.

The machine represented in the drawings is a horizontal machine, its work table being disposed in the horizontal plane, but it will be obvious that said table may be vertically disposed in a vertical machine.

The frame comprises the base *a*, slide-member *c* and drive shaft members *d* and

e, all rigidly cast as one piece. The slide-member *c* may be said to represent the stem of a T-shaped frame, whose head comprises the members *d*, *e*, which have outwardly turned right-angled extensions *d*², *e*², such parts being rigidly supported from the base *a*.

The extensions *d*², *e*², have fitted to them opposite bearings *f*, *f*², for a stationary shaft *f*³, over which is anti-frictionally mounted a long sleeve *f*⁴ carrying a drive pulley *f*⁵ at one end and one of the band pulleys *f*⁶ at the other end. The anti-frictional mounting of the sleeve may conveniently be by ball bearings.

The slide-member *c* of the frame is substantially of open box construction to accommodate a rigidly built bracket *g*, traversing screw devices therefor, and locking devices whereby the position of said bracket upon the slide member is rigidly clamped after adjustment to put the necessary tension on the endless band.

Said bracket *g* constitutes a mounting for an adjustable endless-band pulley *h* mounted to revolve upon a shaft *h*² whose ends are carried in bearing pieces *h*³, *h*⁴, applied to the arm extensions of the bracket *g*, the bearing piece *h*³ being pivoted to the bracket *g* by the pivoting pin *h*⁵ and the bearing piece *h*⁴ being provided with a slot *h*⁶ and a clamping pin *h*⁷ whereby this bearing piece in adjusted position upon the bracket *g* may be clamped to said bracket, the shaft *h*² of this pulley being therefore capable of being set at a slight angle to the shaft *f*³ to cause the endless band, indicated at *y* Fig. 4, to have its running position over the two band pulleys *f*⁶, *h*, changed to nearer the one side than the other.

The bracket *g* is applied to the machined facing *c*² of the slide member *c* to traverse there-along truly to regulate the distance between the two band pulleys *f*⁶, *h*, for the purpose of tensioning the band *y* said traverse being carried out by said bracket *g* having as part of it a screw box *g*² engaged by a traversing screw *i* mounted within the slide member *c* longitudinally to revolve only, said traversing screw being rotated from the milled head *i*².

The bracket *g* engages the slide-member *c* with tongue and groove engagements, the tongues being represented by the edges of

the longitudinal slot c^3 of the slide-member, and the grooves correspondingly formed in the sides of the base of the bracket g as indicated by the dotted lines g^3 , such 5 tongue and groove engagements truly guiding the traverse of the bracket upon the slide-member. After the position of the bracket g has been adjusted upon the slide-member c it is rigidly clamped to said slide-member by a bolt g^4 carried by the bracket g passing transversely through the slide-member to be engaged by a screw nut g^5 working against a clamping block g^6 which 10 abuts against the inner face of that part of the slide member in which the slot c^3 is 15 formed, so that by operation of the bolt and nut and clamping block the bracket g can be rigidly clamped to the slide member c .

Any form of bolt clamping devices may 20 be used for rigidly fixing the bracket g to the slide member c after the tension on the endless band y has been adjusted.

The work table j provides the flat working surface j^2 over which the endless band y 25 travels between the two band pulleys f^6 , h . This table along one side of it is formed with a rigid extension j^3 transversely slotted at j^4 , j^5 . Screw bolts q pass through these 30 slots and into the slide member c to clamp the table rigidly onto said slide member, the slots allowing of the position of the table to be adjusted relative to the edge of the endless band y so that the outer edge j^6 of said table may be either set flush with 35 the adjacent edge of the band or inwards of it, or beyond said edge, as desired. This work table j can also be entirely and readily removed from the machine in cases where work cannot be performed with the table 40 in position, as, for instance, in grinding or polishing spherical work.

The outer end of the slide-member c , which as before stated is substantially of 45 open box construction, is closed by an attached plate l which on being detached can be removed from the slide member together with the traversing screw i clamping bolt g^4 et cetera and bracket g , as one piece.

Having now described my invention what 50 I claim and desire to secure by Letters Patent is:—

1. An endless band grinding and polishing machine comprising a substantially T-shaped frame structure of which the stem is of open 55 box-like construction to form one portion of a slide member and whose head forms a support for a drive shaft, a drive shaft rotatable in said support, a drive pulley and an endless band pulley carried by said shaft, a bracket mounted to slide longitudinally of said slide member and carrying the 60 other portion of the slide member, a second endless band pulley rotatably mounted on said bracket, an adjusting screw extending longitudinally of the slide member and en-

gaging said bracket for adjusting the latter longitudinally of said slide member, and clamping means extending transversely of said slide member and engaging said bracket to lock the latter in adjusted position. 70

2. An endless band grinding and polishing machine comprising a base member, a slide member integral with said base member and having arms extending laterally from one of its ends, each of said arms having a right-angled extension, a drive shaft rotatably supported between said extensions, a drive pulley and an endless band pulley carried by said shaft, a bracket supported by and slidable longitudinally of said slide member, a second endless band pulley rotatably mounted on said bracket in alinement with said first-named endless band pulley, and means carried bodily by the bracket for angularly adjusting said last-named pulley 85 on said bracket.

3. An endless band grinding and polishing machine comprising a slide member of open box-like construction, a drive pulley and an endless band pulley rotatably supported at one end of said slide member, a bracket having tongue and groove connection with said slide member for adjustment longitudinally of the latter, a second pulley rotatably mounted on said bracket, an adjusting screw extending longitudinally of 90 said slide member and having threaded engagement with said bracket for adjusting the latter longitudinally of the slide member, clamping means extending transversely 95 of said slide member and engaging said bracket for securing the latter in adjusted position, and a plate detachably mounted on said slide member forming a closure for one end thereof and supporting said adjusting 100 screw whereby said bracket, adjusting screw and clamping means may be detached as a unit from said slide member.

4. An endless band grinding and polishing machine comprising a slide member, a pulley rigidly supported for rotation at one 110 end of said slide member, a second pulley rotatably supported at the other end of said slide member and adjustable toward and away from said first-named pulley and a 115 table resting on said slide member and adjustable transversely of the latter, said pulleys adapted to carry a movable grinding and polishing belt across said table.

5. An endless band abrasive machine, including a base, a T-shaped frame mounted horizontally on said base, the terminals of the head of the T being provided with alined bearings, a combined drive pulley and band pulley journaled in said bearings, a 120 bracket having two extensions, cooperative means carried by the frame and the bracket for adjustably connecting the bracket to the frame, two bearings adjustably connected to the two extensions of the bracket, and a band 125

pulley journaled in said bearings and capable of being alined or placed at an angular position relatively to the first pulley, and an abrasive band mounted upon both pulleys.

6. An endless band abrasive machine, including a base, a T-shaped frame mounted horizontally on said base, the terminals of the head of the T being provided with alined bearings, a combined drive pulley and band pulley journaled in said bearings, a bracket having two extensions, said bracket being provided with a projection and the frame being provided with a slot for slidably re-

ceiving said projection, a screw for imparting sliding movement to the bracket, a locking screw for locking the bracket in adjusted position, two bearings adjustably connected to the two extensions of the bracket, a band pulley journaled in said bearings and capable of being alined or placed at an angle relatively to the first pulley, and an abrasive band mounted upon said pulleys.

In testimony whereof I have hereunto set my hand.

ROBERT CHARLES TURNER.
